[57] CLAIM

The ornamental design for an equilateral torque drive double-ended socket wrench for hexagonal fasteners, as shown and described.

DESCRIPTION

FIG. 1 is an overall left open end to right end perspective view of an equilateral torque drive double-ended socket wrench for hexagonal fasteners, showing my new design;

FIG. 2 is a reverse perspective view, exposing the open right end of FIG. 1, thereof;

FIG. 3 is an elevational side view, which is a mirror image of the opposite elevational side view, thereof;

FIG. 4 is a left open end elevational view of FIG. 1 and 3, thereof; and,

FIG. 5 is a right open end elevational view of FIG. 2 and FIG. 3, thereof.
